SLIDING WINDOW

Filed Aug. 11, 1930

Inventor:
A. Herman

By: Marks Allen
Attest.

UNITED STATES PATENT OFFICE

ALEXANDER HERMAN, OF BERLIN, GERMANY

SLIDING WINDOW

Application filed August 11, 1930, Serial No. 474,484, and in Germany January 26, 1927.

This invention relates to a sliding window adapted to be lowered into the parapet of the window with a covering ledge, adjustable in two positions, mounted on the window frame, and consists in this, that the ledge is moved inwards or outwards when the window is raised and lowered, by positive guiding in the parapet of the window, being moved inwards by striking the parapet when the window is lowered, and being moved outwards by a spring when the window is raised, so that the movement of the ledge is effected wholly by raising and lowering the window. Such an automatic adjustment is known in itself, but the ledge is mounted on the parapet of the window and its positive connection with the window frame is effected by special rack gearing. Moreover it projects when the window has been lowered and is then freely rotatable, since the positive connection is broken.

Four constructional forms of the invention are illustrated in the accompanying drawings in which

25 Fig. 1 is a vertical fragmentary sectional view through the window and parapet.

Fig. 2 is a transverse sectional view taken above the ledge.

30 Fig. 3 is a fragmentary vertical sectional view of a modified form of the invention.

Fig. 4 is a transverse sectional view taken above the ledge of Fig. 3.

35 Fig. 5 is a fragmentary vertical sectional view of another modified form of the invention.

Fig. 6 is a similar view of another modified form of the invention.

In the construction according to Figures 1 and 2, a ledge *b* stretching over the breadth of the window is jointed to the lower frame *a* of the window, e. g. a hollow metal frame, close to its lower edge, the ledge being guided in a vertical groove *d*, curved at the upper end, by lateral guiding rollers *c*. The vertical part of the groove is inside the parapet *e* of the window.

The mode of operation is at once clear from the drawings. In the position shown in

position by the groove *d*, while when the window is lowered, the rollers *c* are first pushed to the ends of the grooves and the ledge *b* with its axis of rotation is lowered until it reaches the position shown in broken lines in Fig. 1.

In the construction shown in Figs. 3 and 4, the covering ledge *f* is formed as a sector which can swing about the point of rotation *g* and which is mounted so as to slide in a slot *h* in the frame *a* and is held in the working position by a spring *i*. The sector is connected with the axis of rotation *g* by side walls *k* which bear against the guiding bar *b* which is curved at the upper end with an oblique edge. When the window is lowered, the sector is pressed into the frame *a* by the guiding bars.

In the construction according to Fig. 5 the protecting ledge *m* can swing, as in the other cases, but is held in its working position by a spring *n*. When the window is lowered rollers on the ledge *m* run on a rail or on the wall of the parapet *e* of the window and turn the ledge *m* upwards.

In the construction according to Fig. 6, the ledge *o* is carried in straight guides *p* in the interior of the frame *a*, and has oblique surfaces *r*, by which it is pressed into the frame when the window is lowered, and when the window is raised to its highest position it is pressed out by a spring.

What I claim is:—

1. A sliding window adapted to be lowered into the parapet of the window, having a covered ledge mounted on the window frame and means for guiding the free edge of the ledge, to cause the same to alternately swing from a downwardly inclined position to an upwardly inclined position.

2. A sliding window adapted to be lowered into the parapet of the window, having a covered ledge rotatably mounted on the window frame, and grooves in which the free edge of the ledge engages for guiding the same, to cause said ledge to swing alternately from a downwardly inclined position to an upwardly inclined position.

3. A sliding window adapted to be lowered into the parapet of the window, having a

covered ledge rotatably mounted on the window frame, guiding means for guiding the free edge of the ledge to cause the same to swing alternately from a downwardly inclined position to an upwardly inclined position, and spring devices for holding the ledge in contact with the guiding means when in its upwardly inclined position.

4. A sliding window adapted to be lowered into the parapet of the window, having a covered ledge slidably mounted on the window frame and means mounted in the parapet for guiding the free edge of the ledge, side pieces on the ledge and pivotally connected with the frame and adapted to slide on the guiding means, and spring devices connecting the ledge and window for holding the ledge in contact with the guiding means.

5. A sliding window adapted to be lowered into the parapet of the window, having a covered ledge mounted on the window frame, and bars adapted for intimate engagement with the ledge for guiding the free edge of the ledge during sliding movement of the window.

6. A sliding window adapted to be lowered in the parapet, a spring-actuated covering ledge mounted on the window, said covering ledge being mounted on the window in such manner that the lower side of the window is entirely free for the attachment of supporting means.

7. A device according to claim 6, characterized by the fact that the fulcrum of the covering ledge is located on the front side of the window.

In testimony whereof I have signed my name to this specification.

ALEXANDER HERMAN.
